(57) **CLAIM**

We claim the ornamental design for a cable rail, as shown and described.

DESCRIPTION

FIG. 1 is a perspective view of a cable rail showing our design;

FIG. 2 is an end view thereof;

FIG. 3 is a rear elevational view thereof;

FIG. 4 is a front elevational view thereof; and,

FIG. 5 is a top plan view thereof with the bottom plan being identical.

The broken lines shown represent unclaimed subject matter and form no part of the claimed design.

The cable rail is shown with a symbolic break in its length. The appearance of any portion of the article between the break lines forms no part of the claimed design.
